UNITED STATES PATENT OFFICE.

ABNER AVERY BEVIN, OF EAST HAMPTON, CONNECTICUT.

DESIGN FOR A BELL.

SPECIFICATION forming part of Design No. 31,584, dated October 3, 1899.

Application filed August 12, 1899. Serial No. 727,076. Term of patent 7 years.

To all whom it may concern:

Be it known that I, ABNER AVERY BEVIN, a citizen of the United States, and a resident of East Hampton, in the county of Middlesex and State of Connecticut, have invented a new and original Design for a Bell; and I do hereby declare the following, when taken in connection with the accompanying drawings, to be a full, clear, and exact description of the same, o and said drawings constitute part of this specification, and represent, in—

Figure 1, a plan view of the bell, and Fig. 2 a view in side elevation of the same.

My invention relates to a design for bells, 5 and more especially to the class of bells known as "cow-bells." This bell is of circular form when viewed in plan and is smaller in diameter at the top than at the bottom.

A loop appears at the top of the bell, the o top being formed nearly in a horizontal plane, but sloping slightly downward to a point where the sides of the bell begin. The contour-lines of the bell when viewed in elevation extend downward for a considerable dis- 5 tance and gradually separate, the degree of separation gradually increasing toward the bottom, at which point the lines flare out-

ward quite abruptly, and then extend downward for a slight distance to the bottom line. The contour-lines joining the top and sides 30 are of irregular shape, as are also the lines joining that portion of the sides extending in a nearly vertical direction with those at the portion of the bell flaring abruptly outward. The contour-lines of the sides of the bell in 35 fact have a slightly-concaved appearance when the bell is viewed in elevation. Near the top of the body part appears, arranged in a row extending around the bell, a conventional form of flower called a "daisy." Underneath this row of daisies a appears a number of Greek crosses b, arranged in a circumferential line. 40

The material feature of the design consists in the surface ornamentation, consisting of the 45 representation of daisies and Greek crosses arranged thereon.

I claim—

The design for a bell substantially as herein shown and described.

ABNER AVERY BEVIN.
